UNITED STATES PATENT OFFICE.

ERNEST G. GOODWIN, OF NEW YORK, N. Y., ASSIGNOR TO STANDARD COUPLER COMPANY, OF NEW YORK, N. Y., A CORPORATION OF NEW JERSEY.

DRAFT GEAR.

Application filed October 25, 1921. Serial No. 510,272.

To all whom it may concern:

Be it known that I, ERNEST G. GOODWIN, a citizen of the United States, residing at New York, in the county of New York and State of New York, have invented certain new and useful Improvements in Draft Gears; and I do hereby declare the following to be a full, clear, and exact description of the same, reference being had to the accompanying drawings, forming part of this specification.

This invention relates to shock absorbing devices and is shown in one particular embodiment as a standard friction draft gear for use in connection with railway rolling stock. It will be readily apparent, however, that the various details forming parts of the invention may be used in other connections as for example in car truck shock absorbers, automobile truck bumpers, etc.

The object of the present invention is to improve various details of devices of the character stated so that a complete whole may be had which shall be serviceable under all conditions.

In the drawings,—

Figure 1 is a vertical central longitudinal section through the device with the parts in open position.

Fig. 2 is a similar view but with the parts in closed position.

Fig. 3 is a vertical section on line 3—3 of Figure 1.

Fig. 4 is an end view of one of the barrels looking from the smaller end of the barrel.

Fig. 5 is an end view of the screw.

Fig. 6 is a fragmentary section taken on line 6—6 of Fig. 4.

Fig. 7 is a section taken on line 7—7 of Fig. 4.

Fig. 8 is a view taken on line 8—8 of Fig. 5.

Fig. 9 is a view taken on line 9—9 of Fig. 5.

Figs. 10 and 11 show modifications.

The friction draft gear illustrated as showing an embodiment of my invention consists of a pair of similar barrels each having a head 10 and a cylindrical portion 11, the cylindrical portion of one of the barrels being grooved as at 12 to receive the right hand threads 13 of the screw member and the cylindrical portion 11 of the other barrel being grooved as at 14 to receive the

left hand threads 15 of the screw. The heads or end plates of each of the barrel members are connected to the cylindrical portion of the barrel by means of short vertical stiffening ribs 17 and by four diagonal stiffening ribs or flanges 19.

The screw is a single cylindrical piece of metal having a partition 22 at its middle point in which is formed a central hole 23 for the passage of a through-bolt when one is employed. This hole may be of the same diameter as the inner diameter of the coiled springs 25 and 26. The inner ends of the springs abut against shoulders or seats 27 formed on the partition, on opposite sides, as shown in full and dotted lines in Fig. 5. The outer or opposite end of the spring 25 seats against a shoulder or seat 28 in the barrel and the corresponding end of the spring 26 against a similar seat, not shown in the drawings, but exactly similar to the seat 28.

Each of the seats for the springs is made parallel with the ends 29 of the springs, these spring ends being preferably in a plane at right angles, that is, normal to a central helical line through the metal of the spring; in other words, the end faces of the spring are normal to the axis of the bar from which the spring is made before it is wound into the helical shape shown. In the making of ordinary draft gears of this type the spring must be flattened or have otherwise a finished end, whereas, in the form shown in the drawings the spring may be wound without regard to its end and may be later cut off into predetermined lengths with ends bearing the correct relation to one another. The seats or stops 27 and 28, would, in the usual course of manufacture, be cast in both the gear ends and in the central screw piece and may either be in the form of a continuous spiral with the end of the spiral forming a stop, or, to lighten the structure, portions of the spiral may be omitted, leaving separated projections 27^a, 28^a on which the final convolution of the spring rests when fully compressed or driven up solid.

Particular attention is called to the fact that each of the springs is so made that the spring will unwind as the gear is closed under load, this being a novel feature, all other gears winding the springs as the gears are closed. This, while universal, is disadvantageous in that the spring has to be an-

nealed after winding in order to form the properly shaped ends. Attention is also called to the important feature that the spring is non-circular in cross section. By 5 using a bar of square or rectangular cross section rather than a circular bar it is possible to increase the spring capacity with the same thickness of bar wound on a core of the same diameter by nearly three-quarters. 10 I find it preferable in order to secure a high capacity gear to form the spring of a bar of rectangular section wound on edge as shown in the drawings.

The usual square screw thread has been 15 eliminated in this type and the sloping face threads 13 and 15 substituted. By sloping the threads as shown in the various figures the manufacture of the barrels and of the screw, both of which are of cast metal, is 20 much simplified as the tapered thread aids in the drawing of the patterns, this applying to both faces of the threads. It will be readily understood that I may form either the working face of the thread or the rear 25 face square thus securing part of the advantage, but not all. A second advantage and one which was found to be of greater importance than the simplicity of manufacture is the ability to change or increase the 30 capacity of the gear and also secure uniform regularity or smoothness of action by changing the slope on the working face of the threads. Obviously the greater the pitch or lead of the screw the smaller the 35 angular movement as the heads approach each other and in order to maintain the capacity the slope of the working face of the threads is designed to give the desired increased friction due to the wedging action. 40 From the above it is clear that the capacity of the gear may be changed by changing the pitch or lead or by changing the slope or incline of the working face of the threads or both.

45 As will be seen from Fig. 3 six threads are cast on the screw, this number of course being arbitrary. Five of these threads are of the same size, but the other, a master thread 33, is wider than the other five so as to prevent an incorrect assembly of the device. Each of the heads has a single master thread and the screw has a corresponding groove 34 which may be seen at the left hand side of Fig. 5. In view of the 50 number of threads it would be very easy to assemble the gear incorrectly if each were of the same cross section so that when closed the end plates would not be in the same parallel plane longitudinally of the gear or 55 in case the heads were forced into the same plane one end of the gear would be closed before the opposite end. By providing a master thread, such as shown at 33, the gear can only be assembled in one way, this master thread being so located that when the

end pieces are screwed on they will both come to the transverse center line of the gear and at such time will be in the same plane. While there are numerous other ways of preventing incorrect assembly the 70 arrangement shown has been found particularly useful and advantageous in that it takes no capacity from the gear, is no more expensive to manufacture than equal size threads, and always prevents incorrect assembly of the gear even after the parts are 75 very much worn.

In order to provide means for the escape of dust, water, or grit that may tend to collect in the gear and hinder its action, a 80 number of holes such as 35 are provided, these holes being so located that whether the gear is used vertically or horizontally one of the holes 35 will be at the bottom. The holes are therefore preferably substantially 85 90° apart in each head.

Referring now particularly to Figs. 3 and 5, the screw is shown split as at 36 forming a plurality of tongues 37 here shown as five in number each of the splits extending from each end back toward the mid-portion of the screw. Since the springs 25 and 26 in the preferred form illustrated in the drawings, Figs. 1 to 9, are flat on their peripheries and hence afford a great amount of 95 bearing for the encircling member here shown as the screw, it is possible to materially increase the capacity of the gear by forming these tongues so that each of them will be forced inward by the sloping working face of the thread and thereby caused to frictionally grip the outer surface of the springs as the gear is compressed. As the gear is released these segments or tongues, although of cast metal, will be sufficiently 100 resilient to return to normal and offer no obstruction to the return of the spring to open position.

Referring now particularly to Figs. 5, 8 and 9, the central partition 22 of the screw 110 is provided with projections 40 and 40^a of a length substantially equal to the longitudinal thickness of the springs 25 and 26, each of which is provided with a hole 42 or 42^a to receive the pin 40 when the spring is in 115 its correct position. This feature in combination with the master thread which prevents incorrect assembly of the screw and heads prevents incorrect assembly of the spring and the screw, and therefore the 120 combination of the master thread and the pins absolutely prevents incorrect assembly of the gear. It will be readily understood that a pin, similar to 40, may be provided on the spring in which case such pin would 125 fit into a hole or socket in the partition wall 22 of the screw. The spring seats forming part of the central partition in the screw form thick or heavy sections of metal and these are conveniently utilized for the for- 130

mation of radial sockets 44 shown in dotted lines, Fig. 5, and in the detail section, Fig. 9. The holes 44 are not essential, but have been found to be of great convenience in receiving the end of a bar or similar implement by means of which the screw may be turned by hand to draw the heads toward each other in the initial or emergency assembling of the parts.

10 The gears are usually assembled at the factory and are shipped under initial compression to standard dimensions ready for application to the car and for this purpose each head is provided with an internal boss 15 46 having an external socket 47 and perforated as at 48 to receive the tie rod 49. The head 50 of the rod is received in the socket 47 of one head, while the socket 47 of the cooperating head receives the threaded end 20 51 of the bolt 49 carrying a nut 52.

By reference to Figs. 1, 2, 4 and 5, it will be seen that locking or sticking of the threads, such for example as might be caused by the ends of the threads wedging 25 together when the gear is set up solid, is prevented by cutting away or reducing a portion of such ends. Conveniently the meetings ends of the external threads are cut away for one-half their height as at 56 30 (Figs. 1 and 5) and the internal threads for one-half their height as at 57 (1, 2 and 4). By this construction all danger of the threads becoming jammed or locked together is avoided even though one head 35 should advance to the limit of its movement before the other.

By employing right and left hand threads respectively in opposite ends of the gear and spring end abutments facing clockwise 40 at the center and counter-clockwise at the ends (or the reverse) and locating the center abutments or seats 180° apart a very perfectly balanced gear is produced with the employment of a minimum weight of 45 metal and a maximum spring space. The location of the center seats 180° apart permits the ends of the springs to overlap giving greater spring space at each end of the gear.

50 The sloping or inclined faces of the screw threads make it possible to design the gear so as to increase the capacity without increasing the strength of the spring or to use a spring of less strength without decreasing the capacity of the gear all by designing the slope of the thread faces to give the desired results.

While the gear thus far described is that preferred the major features of the invention may be readily incorporated in gears, buffering or shock absorbing mechanism in which the relation of the parts is reversed, that is to say, the spring may be located either inside or outside and the central 60 screw and heads or barrels may have either

internal or external screw threads. Modifications of this character are shown in Figs. 10 and 11.

In Fig. 10 the screw 60 has internal threads while the heads 61 have external 70 threads, while the springs 62 are located on the exterior. In Fig. 11 the same arrangement of the screw and heads is preserved, but the springs 63 are located in the interior 75 of the gear. The details of construction other than above noted may conform to the details of the construction first described, the spring seats, of course, being arranged to suit the location of the springs.

In all cases it is preferred to impart an 80 outwardly bending movement to the springs by reason of the relative angular movement of the parts in closing, the torsional movement being imparted by the reduction in 85 the length or closing of the coils of the springs. Both of these forces are utilized to resist buffing strains but it will be noted that the use of springs of rectangular section with the greater dimension in the plane 90 of the bending movement permits of a greatly increased capacity without requiring proportionally large springs or spring space and hence a high capacity gear may be provided well within the dimensions permissible in railway car practice. It also 95 makes it practicable to construct shock absorbing devices of small size for use in practically any apparatus where such devices are desirable.

The frictional resistance due to the form 100 and operation of the screw thread not only acts to increase the capacity of the gear on compression but it also operates to control the recoil sufficiently to prevent injurious effects but at the same time the return to 105 normal is prompt and effective to restore the controlled parts to normal position.

What is claimed is:

1. In a pressure resisting gear, a pair of 110 relatively rotatable threaded members, a spring having a hole therein and adapted to hold said members in operative position, a lug on one of said members adapted to extend into said hole whereby improper assembly of the device is prevented.

2. In a pressure resisting gear, a barrel, a screw coaxial with said barrel, and a spring located between said screw and said barrel and engaging each of said members, 115 said screw being split to form a plurality of yielding segments.

3. In a pressure resisting gear, an internally threaded barrel, an externally threaded screw fitting therein and movable longitudinally thereof, a spring engaging said screw and said barrel, said screw being split to form a plurality of resilient tongues, thereby increasing the friction by the deflection 125 of said tongues against the surface of said spring.

4. In a pressure resisting gear, a plurality of internally threaded opposing barrel members, a right and left handed screw fitting within both of said barrel members, a 5 spring having a hole therein and adapted to hold one of said barrels and said screw separated from one another, a lug carried by said screw and adapted to extend into the hole in said spring whereby improper 10 assembly of said spring may be detected.
5. In a pressure resisting gear, a hollow threaded screw having a central partition, said screw being split on either side of said partition to form a plurality of segments, a 15 spring within said screw normally out of contact therewith, and means for bending said segments against said spring.
6. In a pressure resisting gear, a plurality of internally threaded barrels, a right 20 and left hand screw having beveled threads and fitting within each of said barrels, a central partition within said screw, a spring on either side of said partition and loosely fitting within said screw and adapted to 25 hold the adjacent barrel member spaced from said partition, said screw being split on either side of said partition to form tongues whereby when said barrel members are forced together said tongues will engage 30 the outer surfaces of said springs thereby increasing the friction of the gear.
7. In a pressure resisting gear, the combination with oppositely disposed head members having cylindrical extensions, an intermediate screw having right and left hand 35 screw threaded engagement with said cylindrical extensions respectively to telescope therewith, spring abutments on the head members facing in the same direction, spring 40 abutments on the screw facing in the same direction and opposite to the direction in which the abutments on the head members face, of coil springs cooperating with said abutments interposed between said parts for 45 holding them in extended relation and both operating to resist rotation of the screw in one direction, and a through-bolt for limiting the movement of said head members away from each other.
- 50 8. A pressure resisting gear having telescoping members with multiple screw

threaded engaging surfaces, and a spring for holding said members extended, one of the screw threads and its cooperating groove being of greater cross sectional area than the others whereby incorrect assembly is 55 prevented.

9. A pressure resisting gear having head members and an intermediate member telescoping together with multiple screw threaded engaging surfaces, a spring holding said members apart, one of said screw threads and its cooperating groove at each end of the intermediate members being of greater 60 cross sectional area than the others to prevent incorrect assembly.

10. In a pressure resisting gear, the combination of head members having cylindrical extensions, with internal right and left hand multiple screw threads, an intermediate 70 screw member having external right and left hand multiple screw threads telescoping into the head members, one of said screw threads of each member being a master thread to prevent incorrect assembly, and right and left hand coil springs both operating to turn the screw member in the same direction.

11. In a pressure resisting gear, the combination with oppositely disposed head 80 members, of an intermediate member telescoping therewith and having a central partition with plane spring engaging seats thereon located on opposite sides of the centre and facing in the same angular direction whereby said seats may be brought more nearly into the same transverse plane, and right and left hand coil springs engaging 85 said seats for resisting compression of the members.

12. A pressure resisting gear having co-operating screw threaded telescoping members of right and left hand pitch, and right and left hand coil springs cooperating with 90 abutment seats on said members, said springs having recesses therein and said abutments having projections thereon, and members in different relation to the right and left hand spring seats and ends of the springs whereby the location of the springs in incorrect 95 relation is prevented.

ERNEST G. GOODWIN.
